US0D1105042S

(12) **United States Design Patent** (10) **Patent No.:** **US D1,105,042 S**
(45) **Date of Patent:** **** Dec. 9, 2025**

(54) **PAIR OF EARPHONES**

(71) Applicant: **Dongguan Hengchang Mould Plastic Co., Ltd**, Dongguan (CN)

(72) Inventor: **Jinwen Chen**, Guangzhou (CN)

(**) Term: **15 Years**

(21) Appl. No.: **35/523,283**

(22) Filed: **Aug. 21, 2024**

(80) **Hague Agreement Data**

Int. Filing Date: **Aug. 21, 2024**

Int. Reg. No.: **DM/242491**

Int. Reg. Date: **Aug. 21, 2024**

Int. Reg. Pub. Date: **Dec. 13, 2024**

(30) **Foreign Application Priority Data**

May 31, 2024 (CN) 202430331849.1

(51) **LOC (15) Cl.** **14-01**

(52) **U.S. Cl.**

USPC **D14/223**

Primary Examiner — Paula Allen Greene

(57) **CLAIM**

The ornamental design for a pair of earphones as shown and described.

DESCRIPTION

1. Pair of earphones

1.1: Front perspective view

1.2: Back perspective view

1.3: Front view

1.4: Back view

1.5: Left view

1.6: Right view

1.7: Top view

1.8: Bottom view

The dash-dash broken lines in the drawings depict the portions of the pair of earphones which form no part of the claimed design.

1 Claim, 8 Drawing Sheets
